FORK OR SIMILAR ARTICLE OF FLATWARE

Robert L. Doerfler, Cheshire, Conn.

Filed Jan. 11, 1965, Ser. No. 83,375

Term of patent 14 years

(Cl. D54—12)

FIG. 1.

FIG. 2.

FIG. 3.

FIG. 4.

FIG. 5.

FIG. 1 is a front elevational view of a fork, showing my new design;

FIG. 2 is a rear elevational view;

FIG. 3 is a side elevational view;

FIG. 4 is a cross sectional view taken on line 4—4 of FIG. 1; and

FIG. 5 is a cross sectional view taken on line 5—5 of FIG. 1.

The design is intended for use on sets comprising forks, spoons, knives and similar articles of flatware.

I claim:

The ornamental design for a fork or similar article of flatware, substantially as shown and described.
